UNITED STATES PATENT OFFICE.

HUBERT STEPHEN CORLETT, OF DOUGLAS, ISLE OF MAN.

TRUCK.

1,405,293.

Specification of Letters Patent. Patented Jan. 31, 1922.

Application filed May 28, 1918. Serial No. 237,105.

To all whom it may concern:

Be it known that I, HUBERT STEPHEN CORLETT, a subject of the King of Great Britain, residing at Douglas, Isle of Man, have invented certain new and useful Improvements in Trucks, of which the following is a specification.

This invention has for its object a method of and apparatus for transporting 10 heavy goods or packages of goods from place to place in a warehouse or elsewhere and stacking them one upon another.

The apparatus comprises a truck having a load supporting surface so arranged as to 15 pick up or assist in picking up one or more articles or packages, and support them in such manner that when tipped one of these articles or packages will stand substantially upright on the floor and form a fulcrum on 20 which the other article or package can be swung up on to the top of the articles or packages immediately below.

The bed or body of the truck is provided with a load supporting platform extending 25 from the prizing bar or shoe at the front end for part of the length of bed and tilted with respect to the bed by means of a riser at the rear, upon which platform one or more articles or packages are carried in a 30 longitudinal position, while the rear end of the bed forms a support for another article or package which is balanced back against the riser and against the end of the package which lies upon the platform so that it takes 35 up a position at about right angles thereto. When the goods are to be stacked in a longitudinal position, they may be placed transversely on the truck.

The invention has been designed more 40 particularly for transporting and stacking loaded bags or sacks and in describing the invention with reference to the accompanying drawings bags or sacks are shown and referred to, but it must be understood that 45 the invention can be used equally well in connection with transporting many other articles of merchandise.

In these drawings:—

Figure 1 is a perspective view of a hand 50 truck with my invention applied thereto.

Figure 2 is a side elevation of a modified construction of truck showing the platform arranged so as to be adjustable.

Figures 3 to 7 inclusive illustrate the 55 successive operations of loading the truck,

transporting the load from one place to another, and stacking the goods.

Referring to Figure 1, the apparatus comprises a hand truck whose bed or body A is carried at one end by wheels B and axle C, and at the other with legs D and handles E for wheeling it along by hand. This bed or body A is provided with a load supporting platform or cradle F extending from the prizing bar or shoe G at the front end 60 for part of the length of the bed and tilted with respect to the bed by means of a riser H at the rear, upon which platform one loaded bag is carried longitudinally, while the rear end of the bed A forms a support 65 for another loaded bag in a standing position, such bag when balanced back resting against the riser H and against the end of the first mentioned bag, so that it takes up a position at about right angles thereto. The 70 bed A may comprise a pair of side rails spaced apart and connected by cross pieces A', and the platform F may also comprise a pair of side rails spaced apart and connected by cross pieces F', the front end resting directly upon the side rails of the bed A, and the rear end supported by the riser members H which form the riser so that the platform F is inclined with respect to the bed A. The front end of the platform 75 has the metal extension arms of the prising bar or shoe G bolted to it, and when the truck is tipped up on end, this prizing bar G can be worked under or be made to insinuate itself under a bag so that when 80 the truck is tilted back the loaded bag will be tilted back also against the platform and lie thereon in a longitudinal position with its end resting against the prizing bar or shoe G. At the handle end of the bed A, 85 the truck is provided with a fixed cross bar I so arranged that when brought against another loaded bag, it will act as a fulcrum to enable the bag to be swung up by hand so as to rest upon the bed A of the truck 90 in an upstanding position.

In the operation of picking up loaded bags from the ground and transporting them to the place where they are to be stacked, the truck is tipped up on end and the prizing bar or shoe G is caused by foot pressure to insinuate itself under a bag (Figure 3), and the handles E are then pulled down so that the loaded bag is elevated off the ground and lies lengthwise upon the platform F. 110

The truck is now turned round and brought into the horizontal position resting upon the legs D with the cross bar I brought close to another loaded bag (Figure 4), which is 5 then tilted against the cross bar I and the bottom end of the bag is swung up by hand so as to invert the bag, the bar I acting as a fulcrum. The second bag now rests upon the bed A and leans against the riser H and 10 against the end of the first mentioned bag, the two bags being at about right angles to each other. (Figure 5.) The truck is now wheeled away to the place where the bags are to be stacked, the weight of the sacks being 15 approximately balanced on the pair of truck wheels. (Figure 6.) The truck is tipped up on end so that the prizing bar G rests upon the floor, the operator steadyng the tipping by foot and hand power, so that one 20 bag will rest on the floor and against a bag which has been previously transported, while the second bag will rest on top of the first bag (Figure 7) in an approximately horizontal position. The top of the first bag 25 acts as a fulcrum on which the second bag is swung up shoulder high by hand onto the top of the bag which was previously transported into position (Figure 8). The truck thus relieved of its load is wheeled away, and 30 the operation is repeated upon other bags. In this method of stacking, the lower tier of stacked bags is always in advance of the bags of the upper tier.

It will be understood that the platform or 35 cradle F with its riser H can be applied to any ordinary hand truck and can be of wood or metal. If desired the front end of the platform can be hinged to the bed A at J as shown in figure 2 and the truck and riser 40 H provided with a number of spaced perforations at J and K through which and through the bed a pin can be passed to lock the platform at any desired inclination and length which can be varied as desired. By 45 removing the pin the said platform can be folded down flat against the bed A, while if the riser be jointed at L such portion can be folded under the bed so as to be out of the way and the apparatus can then be used 50 as an ordinary truck. Or the platform may be detachable.

I declare that what I claim is:—

1. A hand truck for handling and stacking articles, comprising a truck body; wheels 55 mounted on the front end of said body; a prizing bar attached to the front end of said body; an article-carrying cradle of shorter length than said truck body, attached at its front end to the front end of the truck

body and extending rearwardly over said 60 body at an angle thereto; and risers, of shorter length than said cradle, connecting the rear end of the cradle to the truck body forward of its rear end to provide space on the rear end of said body to receive an article, said article being adapted, when in place, to rest against said risers and partially overlap an article on the cradle whereby the latter article may serve as a support on which to pivot the former in removing the same 70 from the truck.

2. A hand truck for handling and stacking articles, comprising a truck body; wheels mounted on the front end of said body; a prizing bar attached to the front end of said 75 body; an article carrying cradle, of shorter length than said truck body, attached at its front end to the front end of the truck body and extending rearwardly over said body at an angle thereto; and risers, of approxi- 80 mately one-half the length of said cradle, connecting the rear end of the cradle at substantially right angles to the truck body forward of its rear end, thereby providing carrying space for an article at the rear of said 85 cradle, said article being adapted, when in place, to partially overlap a similar article on said cradle, which latter article serves as a support on which to pivot the former in removing the same from the truck. 90

3. A hand truck for handling and stacking articles, comprising a truck body; wheels mounted at the front end of said body; a prizing bar attached to the front end of said 95 body; an article-carrying cradle, of shorter length than said body, attached at its front end to the front end of the truck body and extending rearwardly over said body at an angle thereto; risers of shorter length than said cradle, connecting the rear end of the 100 cradle at approximately right angles to the truck body forward of its rear end, said risers and the rear portion of the truck body serving to provide additional article-carrying means; and a rod extending across said 105 truck body rearwardly of said risers, said rod serving as a support over which an article may be fulcrumed into position on the rear end of said truck body against said risers and the end of an article resting on 110 said cradle.

In witness whereof I have hereunto signed my name this 17 day of April, 1918, in the presence of two subscribing witnesses.

HUBERT STEPHEN CORLETT.
